AUGUST KAROLUS, OF LEIPZIG, GERMANY, ASSIGNOR TO RADIO CORPORATION OF AMERICA, A CORPORATION OF DELAWARE

METHOD OF REPRODUCING ACOUSTIC FILMS

Application filed January 28, 1930, Serial No. 424,103, and in Germany February 19, 1929.

The present invention is concerned with the photo-electric reproduction of acoustic films regardless of whether the latter have been made by the blackening or variable density or by the amplitude or variable area methods so-called, and it discloses ways and means adapted to regulate the intensity relations between the higher and the lower frequencies and thereby the timbre and tonal qualities of the voice or music to be reproduced, in so far as it is possible to compensate to any desired degree the decrease of the amplification or transmission factor for very low frequencies. With this end in view the frequency characteristic of selenium cells having, if desired, additions of other substances such as tellurium, is utilized in the following manner:

As shown by the single figure drawing, the fono-film 1 is projected upon an adjustable slit 3 by means of a ray pencil 2 which enlarges the photographic sound record or film optically. Such light as passes through said slit 3 impinges partly upon the photo-electric cell 6, for instance, a potassium cell system of the Elster and Geitel type, while a regulable part of the light is shunted laterally through the shiftable mirror 4 upon the selenium cell 5. Photo-electric cell 6 contains the positive electrode 7 and the negative electrode 8, the latter consisting, e. g., of potassium hydride. Cells 6 and 5 are fed from a battery 9 with the necessary working potentials from taps taken off at different points, and the path of the photo-electric current generated therein is made by way of the joint resistance 10 whose potential fall in well-known manner acts upon the amplifier 11.

Now, while the photo-electric cell 6 inside the entire range or band of frequencies to be reproduced operates in a way free from distortion and inertia, selenium cell 5 furnishes potentials that will be so much higher, the lower the luminous frequency acting thereon. Hence, the means here disclosed allow of an extensive variation of the intensity relations of the higher and lower frequencies and the tonal qualities of the music or voice to be reproduced by the adjustment of mirror 4 and the distribution of the light over the

two cells. For instance, if the amplifier in case of transformer coupling exhibits a decrease in amplification at the lowest frequencies, say, between 20 and 100 cycles or if the loudspeaker connected with the scheme results in a fall in acoustic amplitude, then, as the sensitiveness of cell 5 grows with decreasing frequency, the drop in the overall transmission factor can be compensated ad libitum.

By adding certain substances such as tellurium to the selenium, it is possible to advantageously affect the spectral characteristic as well as the frequency characteristic, and also the conductivity and constancy of the cells in a way advantageous for carrying the present invention into effect.

Having now described my invention, what I claim is:

1. A system for regulating tonal qualities in the reproduction of motion picture film sound records which includes a light translating element for converting fluctuating light intensities into proportionate electric current variations free from distortion throughout the frequency band to be reproduced, and a second light translating element parallelly connected with said first named element and having a sensitivity increasing with decreasing frequency.

2. A system for regulating tonal qualities in the reproduction of motion picture film sound records which includes a light translating element for converting fluctuating light intensities into proportionate electric current variations free from distortion throughout the frequency band to be reproduced, a second light translating element parallelly connected with said first named element and having a sensitivity increasing with decreasing frequency, and means for simultaneously exciting both of said elements by a fluctuating light ray representative of the sound being reproduced.

3. Means for influencing and regulating the transmission factor and tonal qualities for different frequencies in photoelectric reproduction of acoustic films which comprises two photoelectric cells, means for distributing the light representative of the sound being produced in a regulable manner between

- said cells, one of said cells being of such characteristics as to operate practically free from distortion throughout the frequency band to be reproduced, and the other of said cells 5 being of such characteristics as to increase in sensitiveness as the frequency decreases, and means for combining the current regulated by said photo cells to actuate the sound reproducing system.
- 10 4. Means for influencing and regulating the transmission factor and tonal qualities for different frequencies in photoelectric reproduction of acoustic films which comprises two photoelectric cells, means for distributing the light representative of the sound being produced in a regulable manner between said cells, one of said cells being of such characteristics as to operate practically free from distortion throughout the frequency band to 15 be reproduced, and the other being a selenium cell having such characteristics as to increase in sensitiveness as the frequency decreases, a sound reproducing system, and means for combining the current regulated by said photo 20 cells to actuate the sound reproducing system.
5. Means for influencing and regulating the transmission factor and tonal qualities for different frequencies in photoelectric reproduction of acoustic films which comprises, 30 two photoelectric cells, means for distributing the light representative of the sound being produced in a regulable manner between two different cells, one of said cells being of such characteristics as to operate practically free from distortion throughout the frequency band to be reproduced, and the other being a selenium cell containing tellurium having such characteristics as to increase in 35 sensitiveness as the frequency decreases, a sound reproducing system, and means for combining the current regulated by said photo cells to actuate the sound reproducing system.
- 45 6. The method of regulating the quality of sounds reproduced from a motion picture film which comprises converting variations in a light beam representative of the sound being reproduced into a varying electrical current which varies in proportion to the variations of said light beam, converting a portion of said varying light beam into a 50

second electrical current, the intensity of which varies disproportionately with respect to the variations of said light beam, and combining the currents thus produced to produce a current in which the desired frequencies are emphasized to compensate for the inherent lack of response of the reproducing equipment to such frequencies.

7. The method of regulating the quality of sounds reproduced from a motion picture film which comprises producing a varying beam of light representative of the sound to be reproduced, converting variations of said light beam into a varying electrical current varying in proportion to the variations of said light beam, converting a portion of said varying light beam into a second electrical current the intensity of which varies disproportionately with respect to the variations of said light beam, and combining the currents thus produced to produce a current in which certain desired frequencies are emphasized to compensate for the inherent lack of response of the reproducing equipment to such frequencies.

8. The method of regulating the quality of sounds reproduced by sound reproduction apparatus which comprises converting variations representative of the sound being reproduced into a varying electrical current which varies in proportion to said variation, converting a portion of said variations into a second electrical current the intensity of which varies disproportionately with respect to said variations, and combining the currents thus produced.

9. The method of regulating the quality of sounds reproduced from a motion picture film which comprises converting variations of a light beam which are representative of the sound being reproduced into a varying electrical current, which varies in proportion to the variation of said beam, and converting a portion of said varying light beam into a second electrical current, the intensity of which varies disproportionately with respect to the variations of said light beam, whereby a current is produced in which the desired frequencies are emphasized to compensate for the lack of response of the reproducing equipment to such frequencies.

AUGUST KAROLUS.
